UNITED STATES PATENT OFFICE.

HENRY KOCH, OF JAMAICA, NEW YORK, ASSIGNOR TO DICTOGRAPH PRODUCTS CORPORATION, A CORPORATION OF VIRGINIA.

TELEPHONE RECEIVER.

Application filed June 28, 1922. Serial No. 571,507.

To all whom it may concern:

Be it known that I, HENRY KOCH, a citizen of the United States, residing at Jamaica, in the county of Queens and State of New York, have invented certain new and useful Improvements in Telephone Receivers, of which the following is a full, clear, and exact description.

This invention relates to telephone receivers, in which undulations or alternations of an electric current are converted into sound waves. An object of the invention is to provide an improved receiver of this type in which the external circuit connections are made within the casing and which is exceedingly light, simple, compact, durable and inexpensive in construction, and efficient in operation. A further object is to provide a receiver of this type in which the binding posts or circuit terminals of the receiver will be relieved of pulling stresses upon the external circuit cable or wires, and in which the internal mechanism will, in a simple and effective manner, be held against rotation in the casing. Other objects and advantages will be apparent from the following description of an embodiment of the invention, and the novel features will be particularly pointed out in claims.

In the accompanying drawing:

Fig. 1 is a sectional elevation of a receiver constructed in accordance with this invention:

Fig. 2 is another sectional elevation of the same:

Fig. 3 is an elevation of the internal mechanism removed from the casing;

Fig. 4 is a sectional elevation of a portion of the receiver;

Fig. 5 is an elevation of certain details; and

Fig. 6 is a plan of a portion of the external circuit cable, showing the anchoring cord.

In the illustrated embodiment, a casing 1 of suitable light material such as aluminum, hard rubber, or phenol condensation products, is provided with an externally threaded open end upon which an apertured ear piece cap is threaded in a manner common to instruments of this type. A shallow dish shaped frame 3, is disposed within and across the casing, and is provided with a peripherally extending flange 4 which overlies the open edge of the casing and is

clamped between the same and the ear piece cap 2. A diaphragm 5 is clamped against and across the peripheral flange 4 of the frame by the ear piece cap 2. A plurality of permanent magnets 6 somewhat circular in shape are disposed face to face and flat against one face of the frame 3, with their corresponding polar ends aligned with one another. Polar extensions 7 are disposed flat against the polar ends of the permanent magnets 6, and bolts or screws 8 pass through the polar extensions 7, the polar ends of the magnets 6, and the bottom wall of the frame 3, and are in threaded engagement with nuts 9 that are held against rotation within pockets 10 in the face of the frame opposite from the magnets. When the bolts 8 are tightened, the polar extensions will be firmly clamped to the polar ends of the permanent magnets and both will be firmly clamped to the frame 3. The opposite polar ends of the permanent magnets are spaced apart a short distance and the polar extensions extend substantially radially of the casing into the central portion thereof and have angular ends 11 which extend parallel to one another through a central aperture 3a of the frame and perpendicular to the diaphragm. The ends 11 terminate in close proximity to but slightly spaced from the diaphragm, as usual in telephone receivers. An electromagnet coil 12 is disposed upon the angular end 11 of each polar extension, so as to modify the magnetic flux passing therethrough with variations in the current passing through the coil, and these coils 12 are connected together in series by a wire 13. Binding posts 14 are provided with reduced extensions 15 which pass through spaced apertures 16 in a plate 17 of insulating material and each reduced extension also passes through an aperture in a conducting strip 18 and a washer 19, the projecting ends of the reduced extensions being enlarged or upset, such as by peening, to firmly rivet a washer and conducting strip to each binding post, and both binding posts with their connected conducting strips and washers to the insulating plate 17 in spaced positions thereon. A second insulating plate 20 abuts face to face against the plate 17 and is provided with apertures 21 in which the conducting strips 18 and rivet washers 19 are disposed with the conducting strips extending edgewise therefrom. Another insulating

plate 22 is disposed flat against the plate 20 to insulate the reduced ends of the binding posts. The plates 17, 20 and 22 are placed in superposed relation up on the frame 3 between the spaced polar ends of the permanent magnet with the binding posts 14 extending upwardly or away from the frame 3. Bolts 23 pass through the frame 3, the insulating plates 17, 20 and 22 and cooperate with nuts 24 to securely clamp these parts and the binding posts to the frame. The conducting strips 18 extend toward the electromagnet coils, terminating in close proximity thereto, and the circuit ends of the coils of the electromagnets are soldered or otherwise suitably secured thereto to form electrical connections between the coils and the binding posts. The insulating plates 17, 20 and 22 serve to insulate the binding posts and conducting strips from one another and from the frame 3. The binding posts are each provided with a transverse aperture 25 in which a terminal 26 of an external circuit wire 27 may be detachably clamped by a set screw 28. The wires 27 pass into the casing through apertures 29 therein, and exteriorly of the casing are united into a common twin wire cable 30.

A pin like member 31 having a head 32 intermediate of its length extends through the permanent magnets at points intermediate their ends, and through the frame 3, into threaded engagement with a nut 33 for clamping the permanent magnets to the frame 3. A spacing washer 34 may, if desired, be disposed between the permanent magnets and the frame 3, and through which the member 31 may pass. The nut 33 is countersunk into a pocket 35 in a face of the frame 3 so as to be held against rotation with the member 31. The other end of the member 31 extends into or through an aperture 36 in the back wall of the casing which prevents rotation of the frame and parts carried thereby within the casing. An anchoring cord 37 is connected to or formed as part of the twin wire cable 30 of the external circuit, passes through an aperture 38 in the casing, around an annular groove 39 in the member 31, and leaves the casing through the aperture 38. The extending free end of the cord is then tied or otherwise anchored to the cable 30, or the component wires 27 thereof, so that any pulling forces upon the cable or external circuit wires will be resisted by the anchoring cord and member 31, which relieves the binding posts of the pulling forces. The member 31 therefore serves the triple function of clamping the permanent magnets to the frame 3, preventing rotation of the internal mechanism within the casing and serving as an anchoring medium for the anchoring cord 37. The casing may be provided with diametrically disposed depression 40 in its pe-

riphery by means of which the receiver casing may be pivotally mounted between the forked resilient arms carried at an end of a head band (not shown).

When access to the interior of the casing is desired, the ear piece cap 2 is unscrewed and the anchoring cord 37 is untied or loosened. The diaphragm may be removed and the frame 3 pulled outwardly. This provides access to the binding posts 14 so that the circuit wires 27 may be connected thereto or disconnected therefrom. The parts may be replaced within the casing in a reverse order, after which the cord 37 may be tightened, and tied or otherwise secured to the cable 30 so as to relieve the binding posts of pulling stresses in the cable. The internal mechanism of the receiver is easily accessible for inspection or repair, or for the connection of external circuit wires thereto.

It will be obvious that various changes in the details and arrangements of parts in the embodiment herein described and illustrated for the purpose of explaining the nature of the invention, may be made by those skilled in the art within the principle and scope of the invention.

I. claim:

1. In a telephone receiver, a casing, sound producing mechanism within the casing and having terminal binding posts, circuit wires entering the casing and connected to said binding posts; a pin carried by said mechanism and coacting with the casing to prevent rotation of the mechanism therein, an anchoring cord connected to said wires and anchored to said pin within the casing to transfer pulling stresses upon the wires directly to said pin and relieve the binding posts of the same.

2. In a telephone receiver, a casing having an aperture, sound producing mechanism within the casing and having circuit terminals, circuit conductors entering the casing and connected to said circuit terminals, a pin carried by the mechanism and entering the aperture in the casing to prevent rotation of the mechanism in the casing, an anchoring cord connected to the cable and anchored to said pin within the casing to relieve the connections between the circuit conductors and the circuit terminals of the pulling stresses upon the conductors.

3. In a telephone receiver, a casing having an aperture in its bottom wall, a removable apertured cap threaded over the open end of the casing, a frame disposed in the casing and having a central aperture and a flange overlying the open edge of the casing, a diaphragm extending across the frame, said diaphragm and frame being clamped across the open edge of the casing by the cap, a permanent magnet disposed flat against the frame, pole pieces disposed flat against the

5 magnet poles and extending into the central portion of the casing, the inner ends of the pole pieces extending parallel to one another and perpendicularly toward the dia-
 10 phragm, terminating in close proximity thereto, screws passing through the pole pieces and magnet ends and cooperating with the frame to secure the pole pieces to the permanent magnet and both to the frame, elec-
 15 19 tromagnet coil windings on the free parallel end portions of the pole pieces, binding posts disposed in the space between the ends of the permanent magnet and to which external circuit wires may be connected, and means 20 connecting the binding posts to the coil windings.

4. In a telephone receiver, a casing having an aperture in its bottom wall, a removable aperture cap threaded over the open end of the casing, a frame disposed in the casing and having a central aperture and a flange overlying the open edge of the casing, a diaphragm extending across the frame, said diaphragm and frame being clamped across 25 the open edge of the casing by the cap, a permanent magnet disposed flat against the frame, pole pieces disposed flat against the magnet poles and extending into the central portion of the casing, the inner ends of the 30 pole pieces extending parallel to one another and perpendicularly toward the diaphragm, terminating in close proximity thereto, screws passing through the pole pieces and magnet ends and cooperating with the frame 35 to secure the pole pieces to the permanent magnet and both to the frame, electromagnet coil windings on the free parallel end portions of the pole pieces, binding posts disposed in the space between the ends of the 40 permanent magnet and to which external circuit wires may be connected, means connecting the binding posts to the coil windings, and a member engaging the permanent magnet at a point intermediate of its poles 45 and clamping the same to the frame, said member having an extension cooperating with the casing to prevent rotation of the frame within the casing.

5. In a telephone receiver, a casing having 50 an aperture in its bottom wall, a removable aperture cap threaded over the open end of the casing, a frame disposed in the casing and having a central aperture and a flange overlying the open edge of the casing, a 55 diaphragm extending across the frame, said diaphragm and frame being clamped across the open edge of the casing by the cap, a permanent magnet disposed flat against the frame, pole pieces disposed flat against the 60 magnet poles and extending into the central portion of the casing, the inner ends of the pole pieces extending parallel to one another and perpendicularly toward the diaphragm, terminating in close proximity thereto, screws passing through the pole pieces and 65

magnet ends and cooperating with the frame to secure the pole pieces to the permanent magnet and both to the frame, electromagnet coil windings on the free parallel end portions of the pole pieces, binding posts disposed in the space between the ends of the permanent magnet, external circuit wires connected to said binding posts, means connecting the binding posts to the coil windings, a member engaging the permanent magnet at a point intermediate of its poles and clamping the same to the frame, said member having an extension cooperating with the casing to prevent rotation of the frame within the casing, and an anchoring cord connected to the circuit wires and said member to relieve the binding posts of pulling forces upon the circuit wires.

6. In a telephone receiver, a casing having an aperture in its bottom wall, a removable apertured cap threaded over the open end of the casing, a frame disposed in the casing and having a central aperture and a flange overlying the open edge of the casing, a diaphragm extending across the frame, said diaphragm and frame being clamped across the open edge of the casing by the cap, a permanent magnet disposed flat against the frame, pole pieces disposed flat against the magnet poles and extending into the central portion of the casing, the inner ends of the pole pieces extending parallel to one another and perpendicularly toward the diaphragm, terminating in close proximity thereto, screws passing through the pole pieces and magnet ends and cooperating with the frame to secure the pole pieces to the permanent magnet and both to the frame, electromagnet coil windings on the free parallel end portions of the pole pieces, binding posts disposed in the space between the ends of the permanent magnet, external circuit wires connected to said binding posts, means connecting the binding posts to the coil windings, and means extending into the casing for anchoring the circuit wires to relieve the binding posts of pulling forces upon the circuit wires.

7. In a telephone receiver, a casing having an aperture in its bottom wall, a removable apertured cap threaded over the open end of the casing, a frame disposed in the casing and having a central aperture and a flange overlying the open edge of the casing, a diaphragm extending across the frame, said diaphragm and frame being clamped across the open edge of the casing by the cap, a permanent magnet disposed flat against the frame, pole pieces disposed flat against the magnet poles and extending into the central portion of the casing, the inner ends of the pole pieces extending parallel to one another and perpendicularly toward the diaphragm, terminating in close proximity thereto, screws passing through 130

the pole pieces and magnet ends and co-operating with the frame to secure the pole pieces to the permanent magnet and both to the frame, electromagnet coil windings on the 5 free parallel end portions of the pole pieces, binding posts disposed in the space between the ends of the permanent magnet, external circuit wires entering the casing and connected to said binding posts, means for 10 connecting the binding posts to the coil windings, a member carried by the frame and cooperating with the casing to prevent rotation of the frame therein, and an anchoring device connected to the member and 15 to the external circuit wires for relieving the binding posts of pulling forces upon the external circuit wires.

8. In a telephone receiver, a casing, mechanism within the casing for converting 20 variations in current into sound waves said mechanism including a frame and a permanent magnet, circuit binding posts for said mechanism within the casing, external circuit wires entering the casing and connected 25 to said binding posts, a cord connected to said circuit wires, a member engaging the permanent magnet and clamping the same to the frame, and an anchoring cord connected to the circuit wires and said member 30 to relieve the binding posts of pulling forces upon the said circuit wires.

9. In a telephone receiver, a casing having an aperture in its bottom wall, a removable apertured cap threaded over the 35 open end of the casing, a frame disposed in the casing and having a central aper-

ture and a flange overlying the open edge of the casing, a diaphragm extending across the frame, said diaphragm and frame being clamped across the open edge of the casing 40 by the cap, a permanent magnet disposed flat against the frame, pole pieces disposed flat against the magnet poles and extending into the central portion of the casing, the inner ends of the pole pieces extending parallel to one another and perpendicularly toward the diaphragm, terminating in close proximity thereto, means for securing the magnet with its pole pieces to said frame, circuit binding posts disposed in the space 50 between the polar ends of the permanent magnet and external circuit wires connected to said binding posts.

10. In a telephone receiver, a casing, a frame in the casing, a permanent magnet carried by the frame, and having spaced polar ends, an apertured insulating plate, a plurality of binding posts each having a reduced extension passing through an aperture of the plate, a conducting strip riveted 60 upon each extension, a second insulating plate in the space between the polar ends and between the first plate and the frame, means for clamping said insulating plates together and to the frame, polar extensions carried by the polar ends of the permanent magnet, and coils carried by the polar extensions and connected to said conducting strips.

In witness whereof, I hereunto subscribe 70 my signature.

HENRY KOCH.
